(57) **CLAIM**

The ornamental design for a graphical user interface module for patient-operated medical device, as shown and described.

DESCRIPTION

FIG. 1 is a top, front, left side perspective view of the graphical user interface module for patient-operated medical device;

FIG. 2 is a top, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top, plan view thereof;

FIG. 8 is a bottom, plan view thereof;

FIG. 9 is a top, rear, and left side perspective view showing the design in an alternate position from that of FIG. 2; and,

FIG. 10 is a left side elevational view thereof.

The broken lines shown are included for the purpose of illustrating portions of the graphical user interface module for patient-operated medical device that form no part of the claimed design.
